UNITED STATES PATENT OFFICE.

TRACY BARBOUR HATCH, OF ALHAMBRA, AND EDWIN WALTER GOESER, OF LOS ANGELES, CALIFORNIA.

SUCTION-CLEANER.

980,944.

Specification of Letters Patent. Patented Jan. 10, 1911.

Application filed September 27, 1909. Serial No. 519,713.

To all whom it may concern:

Be it known that we, TRACY BARBOUR HATCH and EDWIN WALTER GOESER, citizens of the United States, and residents, respectively, of Alhambra and Los Angeles, California, have invented a new and useful Suction-Cleaner, of which the following is a specification.

Our object is to construct a self-contained portable machine for gathering the dust from floors, carpets, furniture, and the like; and our invention consists of the novel features herein shown, described and claimed.

A suction cleaner embodying principles of our invention includes: A, a carriage forming a chamber adapted for receiving and carrying a suction-mechanism, a motor, a dust receptacle, and a suction-nozzle for the dust-receptacle, and provided with a handle for moving and guiding the machine. B, a suction mechanism mounted in the chamber of the carriage. C, a motor mounted in the chamber of the carriage. D, a dust receptacle mounted removably in the chamber of the carriage. E, a suction-nozzle for the dust receptacle.

The operator rolls the carriage about upon the floor, the motor being connected to a lamp socket, the weight of the machine pressing the suction-nozzle upon the floor, the edges around the inlet to the nozzle forming scrapers for engaging the floor and loosening the dirt, the dust laden air passing through the suction-nozzle and into the dust-receptacle where the dust is retained and the air passing through the dust-receptacle and through the suction-mechanism and through the motor thereby cooling the motor, and the suction-mechanism being provided with means for oiling, flushing and cleaning without removing from the chamber.

Figure 1 is a perspective of a traveling suction-cleaner embodying the principles of our invention. Fig. 2 is a vertical longitudinal section on the line 2—2 of Fig. 1 and looking in the direction indicated by the arrow. Fig. 3 is a view analogous to Fig. 2 and showing the suction-mechanism and motor as an integral device removed from the chamber. Fig. 4 is a view analogous to Fig. 2 and showing the suction-nozzle and dust-receptacle cap removed from the cham-

ber. Fig. 5 is a perspective of the foraminous dust receptacle sack removed from the chamber and removed from the cap. Fig. 6 is a perspective of the piston cylinder casting of the suction-mechanism. Fig. 7 is a cross-section of the suction-mechanism and taken on the line 7—7 of Fig. 3. Fig. 8 is a vertical sectional detail through one of the axles on the line 8—8 of Figs. 1 and 9. Fig. 9 is a cross-sectional detail on the line 9—9 of Fig. 8. Fig. 10 is a sectional detail on the line 10—10 of Figs. 1 and 2 and showing the brush mounting for the motor. Fig. 11 is a perspective of one of the suction-mechanism piston vanes.

The traveling carriage A is shown in Figs. 1, 2, 8 and 9. The main frame is a cored and machined casting and with its fittings comprises the cylindrical body 1, having the main chamber 2 extending from end to end and normally open at both ends, there being a finished transverse face 3 and an internal-screw-thread 4 at the front end, a bifurcated transversely bored axle-boss 5 extending downwardly from near the front end, an axle 6 mounted in the bore of the axle-boss 5, a wheel 7 upon the axle 6, the axle-bosses 8, one on each side low down and near the rear end, the rubber-tired-traction-wheels 9 having the finished hubs 10, the handle bail 11 having eyes fitting upon the hubs 10, the handle stops 12 to be engaged by the handle-bail when it is desired to raise the front end of the machine, the handle 13 for the handle-bail, the headed axles 14 inserted through the hubs of the traction-wheels into the axle-bosses 8 and held in place by the set-screws 15; there being an opening 16 in the top of the rear part of the body 1 to receive the electric cords 17^a and for mounting the switch 18^a, and there being vertically aligned screw-threaded openings 17 and 18 for oiling, flushing and cleaning the suction-mechanism, and a screw-threaded opening 19 for the insertion of a screw to hold the suction-mechanism in place; the forward half of the main chamber being smaller in diameter than the rear half because the space is not needed; there being an internal shoulder 20 against which the suction-mechanism stops and a shoulder 21 for locating a dust collecting screen 21^a.

The suction-mechanism B is shown in

Figs. 2, 3, 6 and 7 and is in the form of a rotary-pump. The piston chamber 22 is formed in a casting comprising the piston-case 23; the piston-chamber 22 being bored 5 cylindrical from the rear end and there being an inlet-port 24 through the upper-part of the piston-case on one side of a central vertical longitudinal plane and an outlet-port 25 on the other side of the line, there being 10 an abutting-surface 26 between the inlet and outlet-ports, and there being an upwardly-projecting-lip 27 around the outlet-port to throw the oil and air outwardly away from the piston case; a flange 28 extending upward from the piston-case and from the front side of the abutting-surface 26; a flange 29 extending downward from the piston-case and at the same side of the central vertical longitudinal plane as the inlet-port 15 24, a flange 30 extending upwardly from the piston-case and from the rear side of the abutting-surface 26, the flanges 28 and 30 forming an abutment between the inlet port 24 and the outlet-port 25; the concentric-baffle-plate 31 extending downward from the flange 30 over the outlet-port 25; the flanges 28, 29 and 30 extending longitudinally of the piston-case and substantially radially therefrom; the chamber-head 32 extending transversely from the front end of the piston-case and connecting the flange 29, the flange 30 and the baffle-plate 31, so as to leave the front end of the pump inlet-chamber 33 open toward the dust-receptacle; the chamber-head 34 extending transversely from the rear end of the piston-case and connecting the baffle-plate 31, the flange 29 and the flange 30, so as to close the rear end of the pump-inlet-chamber 33 and close the rear end of 35 40 the pump-outlet-chamber 35; the chamber-head 32 closing the front end of the pump-outlet-chamber 35 and there being an outlet-passage 36 backwardly outside of the baffle-plate and through the chamber-head 34; the oil-cup block 37 between the flanges 28 and 45 50 55 60 65 30; there being an oil-cup 38 formed from the top of the block and an oil passage 39 leading downwardly to the piston-chamber 22 and an oil passage 40 leading downwardly through the piston-case behind the flange 29, said oil passages being preferably in vertical alinement; so that when the pump is in place the oil-cup 38 registers with the screw-threaded opening 17 and there being a screw-plug 41 for said opening 17 to close the oil-cup and so that the oil passage 40 is in alinement with the screw-threaded opening 18, there being a screw-threaded plug 42 inserted in the opening 18 and closing the oil-passage 40; so that the pump may be oiled, flushed and cleaned; the bearing-block 43 extending backwardly from the piston-case and closing the rear end of the piston-chamber 22, the bearing-opening 44 being eccentric to the piston-chamber 22; and the motor-

attaching-arms 45 and 46 extending backwardly from the chamber-head 34, there being an opening 47 in the arm 45 for the passage of the electric-cord and there being an opening 48 to register with the screw-threaded opening 19, so that a screw 49^a may be inserted to hold the motor and pump in place in the main chamber; the casting being turned to finish the peripheral faces of the chamber-heads to fit closely in the main chamber 2 thereby completing the pump-inlet-chamber 33 and the pump-outlet-chamber 35. 75

The rotary-piston-head 49 is cylindrical and of less diameter than the piston-chamber and has a journal 50 extending through the bore of the bearing-block 43 so as to mount the rotary-piston-head eccentric in the piston-chamber; the length of the piston-head fitting the length of the piston-chamber and there being a longitudinal transverse slot 51 through the piston-head from its forward end to receive the piston-vanes 52 and 53, said vanes being held against the inner-surface of the piston-chamber by centrifugal force and said vanes being made of aluminum to reduce the weight thereby reducing the centrifugal force and reducing the friction. The journal 50 has a bore 54 extending from its rear end to receive the shaft of the motor, and a transverse slot 55 extending from the bore 54 to receive the flattened end of the motor shaft. The piston-chamber-head 56 is bolted to the end of the piston-case to close the piston-chamber, and an internally-screw-threaded boss 57^a projects forwardly from the piston-head to receive the screw 57^b inserted through the screen 21^a. 80 85 90 95 100

The motor C is shown in detail in Figs. 2, 3, and 10. The frame 57 of the motor-field fits close in the main chamber 2 and butts against the ends of the motor attaching-arms 45 and 46, the front windings 58 fitting between the arms. The rear motor bearing 59 is formed at the center of a hemispherical-cap-plate 60, said cap-plate having a shoulder 61, which abuts against the end of the cylinder and a flange 62 extends inwardly and fits against the side of the motor-field frame 57, there being air-openings 63 through the cap-plate 60. The motor-shaft 64 is mounted with its forward end in the journal 50 of the piston-head, the front end 65 of the motor-shaft being flattened to fit non-rotatably in the slot 55. After the parts are placed together the screws 66 are passed in through the air-openings 63 and inserted through the flange 62, through the motor-field-frame 57 and 110 115 120 125 130 screw-seated in the ends of the motor-attaching-arms 45 and 46, thus holding the suction-mechanism and motor together as a single organization, as shown in Fig. 3, so that it may be manipulated as a whole 135

and placed in the main chamber 2, as shown in Fig. 2.

The dust-receptacle D is shown in detail in Figs. 2, 4 and 5. The dust-receptacle-cap is a casting comprising the bell-shaped central body 67, having an exterior-screw-thread 68 on its forward and small end and having an outwardly-projecting-sack-rim 68^a on its rear and large end; the annular web 69 extending outwardly back of the screw-thread 68; the exteriorly-screw-threaded-flange 70 extending backwardly from the web 69 and fitting in the thread 4; and the annular flange 71 extending outwardly from the flange 70 and having a finished face 72 to match the face 3, there being a gasket 73 between the faces 3 and 72 to make a tight joint; and the periphery 74 of the flange 71 being knurled. The dust-sack 75 has longitudinal loops 76 around its open end and an endless-elastic-band 77 is located in the loops to contract the end of the sack, so that when the rim 68^a is inserted into the mouth of the sack the elastic-band 77 will contract behind the rim and hold the sack in place and make a tight joint, so that the dust-receptacle may be applied to the main chamber 2, as shown in Fig. 2, and so that when it is desired to empty the sack the cap-plate may be unscrewed, and the sack removed.

The suction-nozzle E is a casting comprising the parallel-lips 78 and 79 between which is the mouth opening 80; the outer surfaces of said lips being rounded so as to run smoothly forwardly or backwardly upon the floor, and the inner faces of said lips being straight so as to form sharp edges to serve as scrapers for loosening the dirt, the rear scraper throwing the dirt into the mouth when the machine moves forwardly, and the forward scraper throwing the dirt into the mouth when the machine moves backwardly; and the neck 81 extending upwardly and backwardly from the lips 78 and 79. A union nipple 82 is screwed into the neck and a union-nut 83 connects the nipple to the cap-plate, so that the dust passing inwardly through the mouth will pass into the sack. The inlet to the dust-receptacle is above the dirt in the sack so that the dirt is not likely to spill out through the nozzle while the machine is right side up on the floor. The motor brushes 65^a are mounted through the cap-plate.

Thus we have constructed a self-contained traveling suction-cleaner. The weight of the forward end of the machine rests upon the suction-nozzle and both lips of the nozzle engage the floor at the same time and it is not necessary to manually press the nozzle upon the floor. The wheel under the front end of the machine is normally raised from the floor and only comes into use when the suction-nozzle is removed. The suction-

nozzle may be removed and a hose nozzle attached for cleaning furniture, closets and the like.

When the motor operates and the machine travels about, the dust-laden air passes into the dust-receptacle, the air passing through the foraminous wall of the sack leaving the dirt in the sack, and the air passes through the suction-mechanism and through the motor, thereby cooling the motor.

We claim:

1. In a suction cleaner, a hollow cylindrical body normally open at both ends, wheels supporting the hollow cylindrical body, a motor mounted in the rear end of the hollow cylindrical body, a pump mounted in the intermediate portion of the hollow cylindrical body and connected to the motor, the forward end of the hollow cylindrical body forming a chamber for the reception of the dust sack, a fitting removably mounted on the forward end of the hollow cylindrical body, a dust sack removably connected to the fitting, and a nozzle carried by the fitting.

2. A hollow cylindrical body, wheels supporting the hollow cylindrical body, a motor in the rear end of the hollow cylindrical body, a pump in the intermediate portion of the hollow cylindrical body, a nozzle removably connected to the forward end of the hollow cylindrical body, and a dust sack removably connected to the nozzle and mounted in the forward end of the hollow cylindrical body.

3. A hollow cylindrical body mounted on wheels, a motor in the rear end of the hollow cylindrical body, a pump in the intermediate portion of the hollow cylindrical body and connected to the motor, a dust receptacle cap removably connected in position to close the forward end of the hollow cylindrical body, a dust receptacle carried by the cap and mounted in the forward end of the hollow cylindrical body, a union extending forwardly from the dust receptacle cap, and a nozzle connected to the union.

4. A hollow cylindrical body normally open at both ends, a motor mounted in the rear end of the hollow cylindrical body, a pump mounted in the intermediate portion of the hollow cylindrical body and connected to the motor, a nozzle connected to the forward end of the hollow cylindrical body, and a dust receptacle mounted in the forward end of the hollow cylindrical body, so that the air passes through the dust receptacle leaving the dust in the dust receptacle, the air passing on through the pump and the exhaust from the pump passing through the motor around the armature, thus cooling the motor.

5. A hollow cylindrical body, two wheels supporting the rear end of the hollow cylindrical body, suction mechanism mounted in

the hollow cylindrical body, said body having a nozzle connected to its front end adapted to support said front end, a bail connected to the hollow cylindrical body, a handle attached to the bail and stops projecting from the hollow cylindrical body to be engaged by the bail so that the hollow

cylindrical body may be tilted upon the wheels by manipulating the handle.
